UNITED STATES PATENT OFFICE.

HERBERT O. ROSS, OF ST. LOUIS, MISSOURI.

RACK OR FILE FOR CORRESPONDENCE AND THE LIKE.

Application filed December 31, 1919. Serial No. 348,612.

To all whom it may concern:

Be it known that I, HERBERT O. Ross, a citizen of the United States, residing at the city of St. Louis, State of Missouri, have invented a certain new and useful Improvement 5 in Racks or Files for Correspondence and the like, of which the following is a specification, reference being had to the accompanying drawings, forming a part 10 thereof.

This invention relates to a certain new and useful improvement in racks or files for correspondence and the like.

The chief object of my present invention is 15 to provide a rack adapted to rest upon a desk or other such support and wherein letters, papers, documents, and the like pertaining or relating to different matters or to different departments of a business may be 20 conveniently filed, on being assorted, for distribution in due course to the particular departments or for ready accessibility for use in connection with the particular matters. Other objects of my invention are to provide 25 a rack or file especially of the kind and for the purpose stated which is comparatively simple and inexpensive in form and construction and neat and attractive in appearance, and in which the number of compartments, and hence the capacity of the rack 30 or file may be increased or decreased with facility and convenience to meet the needs or requirements of any particular use or installation.

With the above and other objects in view, my present invention resides in the novel features of form, construction, arrangement, and combination of parts hereinafter described and afterwards pointed out in the 40 claims.

In the accompanying drawings,

Figure 1 is an end elevational view of a rack or file constructed in accordance with and embodying my invention;

Figure 2 is a broken side elevational view 45 partly in vertical section, of one of the rack sections or units;

Figure 3 is a broken or fragmental plan view of the rack or file, showing one end only 50 thereof;

Figure 4 is an elevational view of one of the end-unit index-card pocket-forming members.

Figure 5 is an elevational view of one of 55 the combined unit-connecting and index-card pocket-forming members;

Figure 6 is a fragmental perspective view of one of the intermediate rack-sections or units;

Figure 7 is a similar view of one of the 60 end rack-sections or units;

Figure 8 is a similar view of the other end section or unit of the rack; and

Figure 9 is a view similar to Figure 3, but 65 showing the other end of the rack.

Referring now more in detail to the said drawings, in which like reference characters refer to like parts throughout the several views, the rack or file is made up of or comprises a pair of end sections or units and, 70 generally in practice, one or more intermediate sections or units.

The one end unit or section A illustrated particularly in Figure 7, comprises a base-member preferably in the form of a suitably 75 elongated rectangular block 1 of wood or other suitable material, block or base 1 having spaced upper and lower faces or walls connected by parallel side walls or faces and being provided adjacent its ends and upon 80 its sides faces or walls with vertically disposed grooves or ways 2, for purposes shortly appearing. Disposed upon and slightly spaced from an end of the block or base 1, is a preferably sheet-metal plate 3 having 85 side-portions 4 bent to extend flatwise upon the opposite side faces or walls of the block 1, the plate-portions 4 having, in turn, block-gripping extensions 5 bent inwardly to fit in a pair of the grooves 2. The plate 90 3 is also provided with a lip-extension 6, which is bent to extend flatwise upon the under face or wall of the block 1, a plate fastening-screw or the like 7 being passed through the extension 6 and into the block 95 1, as shown. The plate 3 thus provides a pocket at the end of the compartment or unit for receiving an index-card by which the contents of the particular compartment may be indicated or designated, the body of 100 the plate 3 being suitably cut away or apertured, as at 14, to provide a sight-opening through which such card is readily visible.

Similarly providing or forming an index-card receiving-pocket at the other or opposite end of the base or block 1, is a plate 8 identically similar in form and construction to the plate 3, except that in lieu of the lip 6, plate 8 is formed or provided with a suitably elongated extension 9, which is bent 105 and adapted to extend obliquely of and upon the under face not only of the base 1 of

the section A, but also of the base member of the next adjacent section. Extending vertically of and upon each side of the base or block 1, and covering the side portions 4 of the end pocket-forming members or plates 3 and 8, are upright panels or walls 10 of suitable height and of suitable material, such as, for instance, sheet metal, heavy card-board, beaver-board, or the like, the 10 panels or walls 10 being rigidly fixed to the base or block 1 in any suitable manner, such as by means of the fastening or securing screws 11. Spot-welded or otherwise suitably fixed to the outer face of one of the 15 walls 10, are angle-members or the like 12, which serve both as supporting-braces for the end-section or unit and also to add an attractive finish to the rack.

The other or opposite end-section B, illustrated particularly in Figure 8, is substantially similar in all respects to end-section or unit A, except that the inner upright panel or wall 10 is omitted, and except further that the plates 3 and 8 of section B 25 are oppositely disposed to the plates 3 and 8 of section A, as seen by reference to Figures 3 and 9.

Each intermediate section C, illustrated particularly in Figure 6, is substantially 30 similar in all respects to end-section or unit B, except that the supporting braces 12 are omitted and each end of the unit is provided with a combined index-card pocket-forming and unit-connecting plate 8, the 35 plates 8 of the section C being oppositely disposed to each other, as also seen by reference to Figures 3 and 9.

Should a rack of but two compartments be desired, the same may be conveniently 40 formed or built up of but two end sections, such as the sections A and B, the obliquely disposed or extending portions 9 of the plate 8 of section or unit A being fixed to the under side or face of the base 1 of section B 45 by screws or the like 13 and the oppositely disposed extension 9 of the plate 8 of section or unit B being similarly fixed to the base of unit A.

Should a rack or file of three compartments be desired, the same may be conveniently formed or built up of two end sections or units A and B and an intermediate section or unit C, the several units being 50 disposed in proper relation one to the other with the section or unit C interposed between the end-units, the oppositely disposed plate-extentions 9 of unit C being fixed as described one to the base of end unit A and the other to the base of end unit B and the 55 plate-extentions 9 of the units A and B being, in turn, fixed to the unit C, as further seen by reference to Figures 3 and 9. In a similar manner, a rack of my invention may 60 with facility be built up or formed to include or comprises, as will now be evident 65

and as seen in said Figures 3 and 9, any desired number of intermediate units, the capacity of the rack being thus readily and conveniently increased or decreased to suit or fit the needs or requirements of any particular use or installation.

It will also be evident that, should a rack of but one unit and one compartment be desired, the end section A will suffice, a plate 3 being substituted in lieu of its said plate 75 8, and its other wall 10 being similarly equipped or provided with the brackets 12.

Thus I provide a rack or file well adapted for the purposes stated and one whose capacity, as before stated, may be increased 80 or decreased with convenience and facility and practically at will, as may be desired, the rack being one which may be produced inexpensively and furnished at low cost, 85 which is an attractive addition to a desk, and which tends largely to the desk efficiency of the user.

I am aware that changes in the form, construction, arrangement, and combination of the several parts of my rack or file may be 90 made and substituted for those herein shown and described without departing from the nature and principle of my invention.

Having thus described my invention, 95 what I claim and desire to secure by Letters Patent is:

1. A rack of the class described including, as a compartment-forming unit, a rectangular floor-member having spaced upper and 100 under walls connected by parallel side-walls, and a separate upright wall flatwise disposed at an end upon and rigidly fixed to a side-wall of the floor-member, the floor-member forming the supporting base of the 105 unit and being adapted to rest at its under wall upon a supporting surface, and said separate wall being approximately flush at its lower edge with the plane of the under wall, and projecting at its upper edge above 110 the plane of the upper wall, of the floor-member.

2. A rack of the class described including a plurality of compartment forming units, each unit comprising a rectangular floor-member having upper and under walls connected by parallel side walls, and a separate upright wall disposed upon and fixed to one of the side walls of the floor-members, the floor members forming the supporting 120 base of the rack and being adapted to rest at their under walls upon a supporting surface, and plates having engagement with the under walls of the floor-member for securing the units together in connected relation. 125

3. A rack of the class described including a plurality of compartment-forming units, each unit comprising a floor-member and an upright wall fixed to the floor-member, in combination with means engaging an end 130

of the floor-member of one unit and having an extension adapted for engagement with the floor-member of the other unit for securing the units together in connected relation.

5 4. A rack of the class described including a plurality of compartment-forming units, each unit comprising a floor-member and an upright wall fixed to the floor-member, in combination with a plate engaging an end

of the floor-member of one unit and having 10 an extension adapted for engagement with the floor-member of the other unit for securing the units together in connected relation.

In testimony whereof, I have signed my name to this specification.

HERBERT O. ROSS.
